UNITED STATES PATENT OFFICE.

HENRY UNTERMEYER, OF NEW YORK, N. Y.

DESIGN FOR A CHAIN.

SPECIFICATION forming part of Design No. 13,558, dated January 30, 1883.

Application filed June 12, 1882. Term of patent 3½ years.

To all whom it may concern:

Be it known that I, HENRY UNTERMEYER, a citizen of the United States, residing at New York, in the county and State of New York, have invented and produced a new and original Design for Chains, of which the following is a specification, reference being had to the accompanying drawings, forming part thereof, in which drawings—

10 Figure 1 is a side view of several links of the chain. Fig. 2 is an enlarged side view of a single link, and Fig. 3 is an enlarged edge view of the link shown in Fig. 2.

The design consists in the novel and ornamental arrangement of links to form the chain hereinafter described, and shown in the annexed illustration, and particularly pointed out in the claim.

Referring to said illustration, A denotes a 20 single link, which is composed of the two rings *a a* and one ring *b*, the rings being connected and preferably rigidly secured with relation to each other, substantially as shown. At the point where the rings *a a* and the ring *b* pass

through each other the rings *a a* are separated 25 sufficiently to receive between them the small ring *c*, which will be secured in position in any convenient manner.

In order to add to the ornamental effect of the chain, the rings *a a* and the ring *b* have a 30 concave outer surface and a convex inner surface, and the small ring *c* has a convex outer surface.

The rings of the construction and appearance above described will be arranged to form 35 the chain in the manner illustrated in Fig. 1.

What I claim is—

The design for watch-chains, consisting of links composed of the rings *a a* and ring *b*, having concave outer surfaces, and the small 40 ring *c*, having a convex outer surface, the rings being arranged with relation to each other substantially as shown and described.

HENRY UNTERMEYER.
